UNITED STATES PATENT OFFICE.

HENRY CHARLES STIFF, OF JOHNSTOWN, PENNSYLVANIA, ASSIGNOR TO THE LORAIN STEEL COMPANY, A CORPORATION OF PENNSYLVANIA.

SWITCH STRUCTURE.

No. 901,752.

Specification of Letters Patent.

Patented Oct. 20, 1908.

Application filed December 2, 1907. Serial No. 404,875.

To all whom it may concern:

Be it known that I, HENRY CHARLES STIFF, of Johnstown, in the county of Cambria and State of Pennsylvania, have invented a new and useful Improvement in Switch Structures, of which the following is a full, clear, and exact description, reference being had to the accompanying drawings, which form a part of this specification.

10 My invention relates to that type of switch structures in which the heel of the tongue is pivotally mounted in a recess in the switch structure without the use of a pivot pin or pintle.

15 The object of my invention is to provide a simple and durable switch composed of a small number of parts.

Another object of my invention is to provide a simple and efficient tightening device 20 for the heel of the tongue.

With these objects in view, my invention consists in the novel construction, arrangement and combination of parts pointed out in the appended claims, and illustrated in 25 the accompanying drawings, in which—

Figure 1, is a plan view of a portion of a switch structure embodying my invention; Fig. 2, is a sectional view on the line II—II of Fig. 1.

30 A is the switch structure and is provided with the usual thread and guard surfaces.

B is the tongue having the enlarged circular heel b, the center of rotation being at a point near the gage line.

35 a is the tongue floor in the switch structure, and a' is a circular recess in the switch structure to receive the circular heel b of the tongue.

At the side of the switch structure A, and 40 in front of the tongue center, is the box C, and projecting from the sides of the box are the lugs c, c; and projecting from the bottom of the box are the projections c', c'.

The periphery of the heel b of the tongue 45 B, is under cut adjacent to the box C at an angle as at b', Fig. 2.

Within the box C, and bearing against the lugs c, c, is the plate D, and passing through a tapped orifice in this plate, is the screw F, 50 having an enlarged head f, which is provided with a series of through orifices f', f', f'.

G is a locking key or plate which bears against the cutaway portion b' of the heel of the tongue and the switch structure, and is

held in contact with these surfaces by means 55 of the screw F.

f² is the screw locking pin. This pin projects through one of the orifices f' and between the projections c', c'. When it is desired to increase or decrease the tension on 60 the screw F, the pin f is raised and used as a lever to rotate the screw, and when the proper adjustment has been effected, the pin is dropped into the position shown, which will keep the screw from jarring loose. 65

The advantages of my invention result from the tongue having a flat circular pivot of a diameter considerably greater than the width of the heel of the tongue and the center of the arc being at a point near the 70 gage line thereof. This enlarged cylindrical heel whose center of rotation is at a point near the gage line in combination with the flat bearing surface greatly prolongs the life of a switch structure, as the load is carried over the center of the heel of the tongue, the load will be equally distributed, so that all points of the heel of the tongue will receive an equal amount of wear, which will prevent the rolling or tilting of the tongue 80 which is common in switches whose tongue receives the load on one side thereof.

By placing the tongue securing member at the side, and in front of the tongue pivot, I am enabled to hold the tongue to the abutting portion of the switch structure; also to receive the thrust of the car wheel when taking the curve. 85

Having thus fully described my invention, what I claim as new, and desire to secure by 90 Letters Patent is:—

1. In a switch structure, a pinless tongue having an enlarged circular heel whose center is at a point near the gage line of the tongue, the bearing surface of the heel being on a line with the bearing surface of the tongue. 95

2. In a switch structure, a pinless tongue having an enlarged circular heel whose center is at a point near the gage line of the tongue, the bearing surface of the heel being on a line with the bearing surface of the tongue, an angular face on the periphery of the heel, and a retaining plate bearing against the angular face. 100

3. In a switch structure, a pinless tongue having an enlarged circular heel whose center is at a point near the gage line of the tongue. 105

tongue, the bearing surface of the heel being on a line with the bearing surface of the tongue, an angular face on the periphery of the heel, and in front of the center thereof, 5 and a retaining plate bearing against the angular face.

4. In a switch structure, a pinless tongue having an enlarged circular heel whose center is at a point near the gage line of the 10 tongue, the bearing surface of the heel being on a line with the bearing surface of the tongue, an angular face on the periphery of the heel, a retaining plate bearing against the angular face, and a screw bearing against 15 the retaining plate.

5. In a switch structure, a pinless tongue having an enlarged circular heel, the bearing surface of the heel being on a line with the bearing surface of the tongue, an angular 20 face on the periphery of the heel, a retaining plate bearing against the angular face, a screw bearing against the retaining plate, and a pin to lock the screw in its adjusted 25 position.

6. In a switch structure, a pinless tongue having an enlarged circular heel whose center is at a point near the gage line of the tongue, an angular face on the periphery of

the heel and a retaining plate bearing against the angular face.

7. In a switch structure, a pinless tongue having an enlarged circular heel whose center is at a point near the gage line of the tongue, the bearing surface of the heel being on a line with the bearing surface of 35 the tongue, an angular face on the periphery of the heel, a retaining plate bearing against the angular face, and an adjusting device to adjust the tension of the plate against the angular face.

8. In a switch structure, a pinless tongue having an enlarged circular heel, the bearing surface of the heel being on a line with the bearing surface of the tongue, an angular 40 face on the periphery of the heel, a retaining plate bearing against the angular face, a screw bearing against the retaining plate, and means to lock the screw in its adjusted position.

In testimony whereof, I have affixed my 45 signature in presence of two witnesses.

HENRY CHARLES STIFF.
